UNITED STATES PATENT OFFICE

2,566,018

INDIVIDUAL SURGICAL DRESSING KIT

Pierre Collignon, Paris, France

Original application August 1, 1947, Serial No. 765,549. Divided and this application April 4, 1950, Serial No. 153,910. In France September 23, 1939

Section 1, Public Law 690, August 8, 1946
Patent expires September 23, 1959

3 Claims. (Cl. 128—87)

1

This application is a division of my co-pending application Serial No. 765,549, filed August 1, 1947, now Patent No. 2,561,844.

The present invention relates to a box or container for dressings and has for its object to provide such a box or container which is adapted to be converted into a splint for supporting a fractured limb.

Another object of this invention is to provide such a convertible container which may be easily opened, and converted into and utilized as a splint by an injured person without assistance from other persons.

A further object is to provide a container convertible into a splint which is especially suitable for emergency or first-aid treatment of persons wounded or injured in road accidents, in camping accidents, or on the battlefield.

Other objects and advantages will appear hereinafter.

In order to facilitate an understanding of the invention, reference is made to the accompanying drawings in which:

Figure 1 is a perspective view of the convertible container assembly;

Fig. 2 is a horizontal cross-section on line II—II of Fig. 1;

Fig. 3 illustrates on an enlarged scale certain details of Fig. 2;

Fig. 4 is a vertical section on line IV—IV of Fig. 1; and

Figs. 5 and 6 illustrate the use of the convertible container as a splint.

As shown in Figs. 1 and 2 of the drawings, the convertible container is composed of two component elements 21—22. These elements are each formed from sheet metal of suitable gauge and press-shaped to a channel-section configuration by bending at right angles the two opposite longitudinal edges thereof, the bent corners being somewhat rounded. Each bent plate 21 and 22 is internally lined with a suitable thickness of absorbent material 23 such as thick felt or slightly compressed cotton wool.

The members 21—22 are connected to each other by an interfitted connection shown in detail in Fig. 3. The side edges of each sheet element are bent as at 24 so as to leave a duct or free space 25 and to form a complementary dove-tailed assembly as at 26. This dove-tail assembly is formed with sufficient play to allow the elements 21 and 22 to be easily separated in subsequent use in the direction indicated by the arrows 27 in Figs. 2 and 3. In adjacent ducts or free spaces 25 there is disposed a strong but flex-

ible steel wire 28 bent to a hairpin shape, as shown in Fig. 1. The wire 28 extends along the vertical edges and across the underside of the elements 21 and 22, and serves to provide the actual connection therebetween.

With the two component elements interconnected as just described, their top and bottom faces are sealed by a lid 29 and a bottom element 30. The lid 29 and bottom member 30 are provided on their rear sides with a projecting plate 31 and 32 respectively, secured thereto as with rivets or spot-welds. The top member 29 acts as the main support for the container and extends a greater distance over the elements than does the bottom member 30.

The projections 31 and 32 serve to secure the assembled container to the user's outer garment, preferably in the precordial or chest region. A simple and practical way of securing the container to the outer garment is by the use of a pair of clips or large safety-pins or the like, which perforate the material of the garment as at the points 33, 34 and 35, 36 respectively. Small shoulders 37 are provided on each of the projections to retain the assembly in a firmly clamped relation to the user's chest.

The two component elements contain a pair of dressing wads 38 (Fig. 4) and also a strap of thick webbing 39 rolled up and attached to the inner felt lining as by adhesive means.

In use, when the injured person requires a dressing, he has merely to firmly grasp with one hand the elements 21, 22 of Fig. 1, and raise them vertically so as to disengage them from the bottom member 30 while keeping them in engagement in the top member 29. The top member 29 will be moved together with its projection 31 in the same direction and the points 33 and 34 will serve as abutments. The elements are then moved slightly forward away from the body and the lower wad of dressing will then freely drop out of the container.

The reverse of the above movement is then accomplished to close the container, and a spare dressing is, in this manner, maintained in reserve.

Should the injury be such as to require the use of both dressings, the interconnected elements 21 and 22, after having been disengaged from the bottom member 30, are then pulled downwards, whereupon the elements are disengaged from the lid 29, the entire contents of the box becoming available.

Should the injury further require the use of a splint, this is provided by the elements 21 and 22,

When the elements 21 and 22 have been disengaged from the lid 29 and the bottom member 30, the two elements are separated by exerting the above-described pull in the direction of the arrows 27 (Figs. 2 and 3). They are then opened or flattened out, bookwise, in a perpendicular plane with the head of the hairpin wire 28 acting as the pivot, and the straight channel-shaped splint shown in Fig. 5 is obtained.

The splint thus produced is adjustable in length since, as shown in Fig. 6, each element 21, 22 may be made to slide any desired distance over the straightened out wire 28.

A further advantage is the ability of the splint to be used in the case of an injury requiring immobilization of a joint, such as the elbow. For this purpose, the elements 21-22 are first slid apart over the wire 28 a suitable distance. Then, in the event the elements are still in their initial angular position, they are folded down, or conversely, if they are already in their straight condition shown in Fig. 6, they are raised by forming another bend in the wire 28. This causes the elements to assume any desired angle and renders them instantaneously adaptable to the particular emergency. When the splint is used in this manner, the web or sling 39 is used to support the splint which in turn supports the injured member.

Having described my invention, I claim:

1. A dressing-carrying container capable of being transformed into a splint comprising two channel-shaped side-forming members juxtaposed so that the ends of the flanges are in contact, said ends of said flanges being bent back upon themselves to form a longitudinal duct, two wires of hairpin formation inserted through said adjacent longitudinal ducts respectively and interconnecting the juxtaposed members, and bottom and top members fitted over the respective open ends of said interconnected side-forming members, said channel-shaped side-forming members being adapted, upon removal of said bottom and top members, to be separated and folded back to form a splint composed of the two channel-shaped members interconnected by the two wires.

2. A dressing-carrying container capable of

being transformed into a splint comprising two channel-shaped side-forming members juxtaposed so that the ends of the flanges are in contact, said ends of said flanges being bent back upon themselves to form a longitudinal duct, two wires of hairpin formation inserted through adjacent longitudinal ducts respectively and interconnecting the juxtaposed members, said wires being slidable within said longitudinal ducts, and bottom and top members fitted over the respective open ends of said interconnected side-forming members, said channel-shaped side-forming members being adapted, upon removal of said bottom and top members, to be separated and folded back to form a splint composed of the two channel-shaped members interconnected by the two wires.

3. A dressing-carrying container capable of being transformed into a splint comprising two channel-shaped side-forming members juxtaposed so that the ends of the flanges are in contact, said ends of said flanges being bent back upon themselves to form a longitudinal duct, two wires of hairpin formation inserted through adjacent longitudinal ducts respectively and interconnecting the juxtaposed members, said wires being slidable within said longitudinal ducts, bottom and top members fitted over the respective open ends of said interconnected side-forming members, and projecting securing plates attached to each of said bottom and top members for attachment to the user's garment, said channel-shaped side-forming members being adapted, upon removal of said bottom and top members, to be separated and folded back to form a splint composed of the two channel-shaped members interconnected by the two wires.

PIERRE COLLIGNON.
